R. M. HUNTER.

PRINTING PRESS.

No. 271,070.

Patented Jan. 23, 1883.

N. PETERS. Photo-Lithographer, Washington, D. C.

UNITED STATES PATENT OFFICE.

RUDOLPH M. HUNTER, OF PHILADELPHIA, PENNSYLVANIA.

PRINTING-PRESS.

SPECIFICATION forming part of Letters Patent No. 271,070, dated January 23, 1883.

Application filed June 5, 1882. (No model.)

To all whom it may concern:

Be it known that I, RUDOLPH M. HUNTER, of the city and county of Philadelphia, State of Pennsylvania, have invented a new and useful Improvement in Printing-Presses, of which the following is a specification, reference being had to the accompanying drawings, which form part thereof.

My invention has reference to printing-presses in general, but more particularly to the means for automatically transferring sheets from one cylinder to another of a printing-press; and it consists in the arrangement of two impression-cylinders with an endless chain 15 of type-form carriages, said cylinders being adapted to print from alternate type-carriages, and a suction device arranged between said cylinders, through the agency of which the paper from one cylinder is transferred to the other cylinder, whereby it is reversed to be 20 printed on both sides, the said suction device being adapted to operate intermittently, so as to hold the paper only for an instant and prevent its printed surface being drawn over the 25 suction-plate, and in details of construction, as more fully set forth hereinafter.

This invention is an improvement upon Letters Patent granted to Henry P. Feister, dated April 18, 1882, and numbered 256,662, and 30 particularly relates to the means by which the sheets of paper are transferred from one cylinder to the other and reversed, said means being substituted for the nippers and auxiliary mechanism in the patent above referred to.

The object of this invention is to provide 35 suitable means by which the paper sheet may be reversed by the aid of suction apparatus and currents of air and prevent its being blurred or smutted. I do not claim the use of suction apparatus, broadly, for this purpose of reversing the sheet, my improvements being the mechanism by which an "intermittent" suction or blast is obtained to be used in the above-specified manipulations of the sheets, and by 40 which they are kept clean.

In the drawings, Figure 1 is an enlarged section elevation of part of the two impression-cylinders and my improved suction reversing mechanism, through the agency of which the 45 sheets of paper are transferred from one cylinder to the other and at the same time re-

versed. Fig. 2 is a side elevation of the suction mechanism removed from the machine, and Fig. 3 is a sectional elevation of the printing-machine complete.

A is the frame of the machine. B are guide-beds secured to the frame, and guide the endless chain of type-form carriages C, which may be supported upon rollers to reduce friction. These carriages carry the type, and may be 50 provided on one or both sides with racks C', which mesh with the teeth D' and E' on the impression-cylinders D and E, and from which said type-carriages receive their motion. These impression-cylinders are two in number, and 55 are provided with impression-surfaces d and e, and also with spaces d' and e', the impression-surfaces being provided in the usual manner with make-readies, and are equal in number to the number of type-carriages C, those d 60 printing from every alternate carriage and those e printing from the carriages omitted. Therefore each of the impression-cylinders prints from one-half of the entire number of 65 type-carriages. The forward ends of each of the impression-surfaces d and e are provided 70 with nippers F, adapted to hold one end of the paper sheets l and cause them to be carried around by said impression-cylinders, and between them and the type on the carriages. 75 These nippers may be actuated by arms f, carrying friction-rollers on their ends, springs f', and cams G and H.

The paper sheets may be fed by hand from the table I, or automatic feeding mechanism 80 may be used, as set forth in the aforesaid patent to Feister, in which the sheets are automatically cut from a roll of paper. The sheet is arrested in feeding position by the stop I', and as it rises the paper sheet is caught by 85 the nippers F, which are closed by springs f' the moment the arms f run off the cam G, and the said sheet is carried around with the revolving cylinder D. Each impression-surface receives a sheet of paper as it passes the table 90 I. The sheet is then carried down and over the type on the carriages C, which has been 95 previously inked by inking-cylinder Q, and is printed on one side. It is then carried up in front of the suction-plate m of the air-box M, 100 through which air is intermittently sucked, and is freed by the nippers and arrested by an

adjustable stop, m' . When the sheet is being drawn up before the suction-plate, the air is shut off by valve-plate M' , whose surface may be provided with holes or slots, and from the bottom or point of box M by valve M^2 ; but the instant the paper is raised the proper height and freed the valve-plate M' and valve M^2 rise, opening the air-ports, and the sheet l is sucked against the plate m and its lower end drawn over against the cylinder E , where it is caught by nippers F . The instant it is caught by the nippers of cylinder E the suction ceases, and a blast of air is forced out of the box M , blowing the paper away from the suction-plate until it has been drawn away clear of the same to prevent smutting of the wet ink. If desired, the blast may be dispensed with and the suction shut off by valve-plate M' and valve M^2 ; or the valves may be shut off and the partial vacuum in box M changed to pressure; but I prefer the alternate suction and blast. The drawings show the arrangement of parts just as the blast has been put on, and the sheet l is shown as blown away from plate m . The valve-plate M' may be operated by an arm, M^3 , secured to a rock-arm, M^4 , passing through the box M , and provided on its outer end with a crank or arm, M^5 . Connecting this arm M^5 and one arm of bell-crank M^7 is a bar, M^6 . This bell-crank M^7 is actuated by a cam, O^2 , secured upon the shaft O , carrying the fan N , and intermediate gear-wheel, D^2 , which meshes with the gear-wheels D' and E' and operates the entire machine. If desired, the fan may be driven by another shaft; but the arrangement shown makes the machine more compact.

The suction and blast are controlled as follows: There are three ports, N' , N^2 , and N^3 , opening into the top of the box or chamber M , and before which a valve, N^4 , reciprocates to connect any two of said ports. Of these ports N' is alternately a blast and suction port. N^2 is always a blast port, and N^3 is always a suction-port. The valve N^4 alternately connects ports $N' N^2$ and $N' N^3$, and is reciprocated or rocked by a rock-shaft, N^5 , provided on the end with an arm, N^6 , to the end of which is hinged the reciprocating bar N^7 , guided by bearing N^8 , and provided on its end with a roller which works against a cam, O' , secured to the shaft O . The port N' communicates with the atmosphere, port N^2 with the periphery of the fan-chamber, and port N^3 with the eye of the fan-chamber. The solid arrows indicate the direction of the currents of air when there is a pressure in the box M , and the dotted lines indicate the currents when there is a partial vacuum in box M . As the paper l is drawn down and about clear of the plate m the valve-plate M' and valve M^2 are closed by cam O^2 , and instantly the cam O' shifts the valve N^4 , connecting the ports $N' N^2$ and allowing the fan N to create a partial vacuum in the box M . The instant the next sheet is brought up into position the valve-plate M' opens its ports

and the sheet is sucked against plate m , and when the nippers F of cylinder E have caught it the valve N^4 is shifted to the position shown, and now the fan is blowing directly into the chamber M .

While I prefer the combined actions of blast and suction, yet it is evident that I may use either one alone by dispensing with either the valve N^4 or valve-plate M' and valve M^2 . Any other suitable mechanism may be used to operate these air-valves, and the valves themselves may be made in various ways without departing from my invention.

The cylinder E carries the sheet a second time over the type-carriages, and it is printed on the opposite side. After being printed on both sides the sheet is carried up a short distance and freed from the nippers by a continuation of cam H , and is carried away from the cylinder by tapes or bands R , which encircle cylinder E and roller r . It then passes between the bands $R R$, and then between bands $R' R^2$ to fly-frame T , which folds the sheets down upon table T' . To this end of the machine may be attached suitable binding, folding, and trimming mechanism, as shown in the patent to Feister, specified hereinbefore.

Having now described my invention, what I claim as new, and desire to secure by Letters Patent, is—

1. In a printing-press, two impression-cylinders provided with a series of impression-surfaces and spaces, and an endless chain of carriages adapted to carry the type-forms, one of said cylinders printing from every alternate type-form and the other printing from those omitted, in combination with an air-box arranged between said cylinders, and having its face perforated, and means, substantially as described, acting intermittently to create a partial vacuum or pressure in said box, by which the sheets are fed from one cylinder to the other after being printed on one side.

2. In a printing-press, two impression-cylinders provided with a series of impression-surfaces and spaces, and an endless chain of carriages adapted to carry the type-forms, one of said cylinders printing from every alternate type-form and the other printing from those omitted, in combination with an air-box, means, substantially as described, to create a suction and pressure therein, and valved orifices opening from said air-box and adapted to cause intermittent suction through said orifices, by which the sheets, when being fed from one cylinder to the other, are transferred without blurring or smutting, after being printed upon one side.

3. In a printing-press, two impression-cylinders, each provided with a series of impression-surfaces and spaces, and an endless chain of type-form carriages, one of said cylinders being adapted to print from every alternate carriage and the other printing from those omitted, in combination with an air-box having a perforated face, a valve intermittently actuated to control the orifices of said box, and

means, substantially as described, actuated intermittently to create a partial vacuum or pressure in said air-box, by which the sheets, when being fed from one cylinder to the other, are transferred without smutting, after having been printed on one side.

4. In a printing-press, two impression cylinders provided with a series of impression-surfaces and spaces, said surfaces being furnished with automatically-acting nippers or clamps to hold the paper sheets, and an endless chain of type-form carriages, one of said cylinders printing from every alternate type-carriage, and the other printing from those omitted, in combination with a feed-table from which the paper is fed to one of said cylinders, and upon which the sheets are held by said nippers, an air-box provided with a suction-surface, intermittently-acting valves to control the suction or passage of air through said suction-surface, by which said sheet of paper is held for a period of time only sufficient to allow the nippers upon the other cylinder to clamp the lower edge of said sheet, the suction-surface then releasing said paper, mechanism, substantially as described, to actuate the nippers upon one cylinder to free the paper when before the suction-surface, and mechanism, substantially as described, to cause the nippers on the other of said cylinders to clamp the paper and draw it off said suction-surface, (the air-blast aiding to effect the transfer without smutting,) and cause it to be printed upon the other side, and means, substantially as described, to create currents of air through said suction-surface and air-box.

5. In a printing-machine, the combination of cylinders D and E, having surfaces *d* and *e* and spaces *d'* and *e'*, type-form carriages C, nippers F, means, substantially as described, to actuate said nippers, suction or air box M, having perforated surface *m*, valve-plate *M'*, fan N, and means, substantially as described, to intermittently actuate said valve-plate, substantially as specified.

6. In a printing-machine, the combination of cylinders D and E, having surfaces *d* and *e* and spaces *d'* and *e'*, type-form carriages C, nippers F, means, substantially as described, to actuate said nippers, suction or air box M, having perforated surface *m*, valve-plate *M'*, arm *M*³, shaft *M*⁴, cam *O*², and connecting mechanism, substantially as described.

7. In a printing-machine, the combination of cylinders D and E, having surfaces *d* and *e* and spaces *d'* and *e'*, type-form carriages C, nippers F, means, substantially as described, to actuate said nippers, air-box M, having perforated surface *m*, ports *N'*, *N*², and *N*³, valve *N*⁴, means, substantially as described, to actuate said valve, and fan N, substantially as specified.

8. In a printing-machine, the combination of cylinders D, E, having surfaces *d* and *e* and teeth *D'* and *E'*, nippers F, means, substantially as described, to actuate said nippers, type-form carriages C, air-box M, ports *N'*, *N*², and *N*³, means, substantially as described, to alternately connect two of said ports to create a suction or blast in said air-box, fan N, shaft *O*, and intermediate gear, *D*², substantially as set forth.

9. In a printing machine, the combination of cylinders D and E, having surfaces *d* and *e*, type-form carriages C, nippers F, means, substantially as described, to actuate said nippers, air-box M, having perforated surface *m*, valve-plate *M'*, ports *N'*, *N*², and *N*³, valve *N*⁴, fan N, and mechanism to actuate said valves, substantially as specified.

10. In a printing-machine, the combination of cylinders D and E, having surfaces *d* and *e*, type-form carriages C, nippers F, means, substantially as described, to actuate said nippers, air-box M, having perforated surface *m*, valve-plate *M'*, means, substantially as described, to intermittently actuate said valve-plate, fan N, and adjustable stop *m'*, substantially as and for the purpose specified.

11. In a printing-machine, the combination of cylinders D and E, having surfaces *d* and *e*, and nippers F, means, substantially as described, to actuate said nippers, type-form carriages C, air box M, having perforated surface *m*, valve-plate *M'*, and valve *M*², fan N, and means, substantially as described, to actuate said valves to control the currents of air through the surface *m*, substantially for the purpose specified.

In testimony of which invention I hereunto set my hand.

RUDOLPH M. HUNTER.
